UNITED STATES PATENT OFFICE.

CHARLES JOHN DREWES, OF NEW YORK, N. Y.

DISPENSING APPARATUS.

1,296,172.

Specification of Letters Patent.

Patented Mar. 4, 1919.

Application filed January 30, 1917. Serial No. 145,416.

To all whom it may concern:

Be it known that I, CHARLES J. DREWES, a citizen of the United States, residing at New York city, in the county of New York and State of New York, have invented certain new and useful Improvements in Dispensing Apparatus, of which the following is a specification.

My invention relates to certain new and useful improvements in apparatus for dispensing soda-water and other liquids, in the modern drug stores and other public places where like waters are dispensed.

A leading object of my invention is to provide a soda-water or like apparatus which will facilitate the prompt dispensing of the liquid; will maintain the syrups in a better and more uniform condition and devoid of danger of the syrup coming in contact with metallic parts, and where there will be no interruption or delay in the service while any one or more of the syrup bottles or containers are being refilled. Other objects of the invention are to provide an apparatus which will preserve the sweetness of the syrup and reduce the liability of fermentation and at the same time present a form of apparatus which is of a highly sanitary character and which is also ornamental and may expose the syrup-jars or bottles to observation at all times.

In the accompanying drawings Figure 1 is a cross sectional view of a soda-water apparatus embodying my invention, showing the parts in elevation. Fig. 2 is a perspective view showing one end of the apparatus.

In carrying out my invention I construct a casing or cabinet of any desired style and size and of such design that it will present a highly attractive article when installed in the store or place where the liquid is to be dispensed. Structurally, the cabinet will be divided horizontally by a shelf or partition, 10, into two compartments, the lower of which, 11, constitutes an ice box with the doors, 12. The partition or shelf, 10, forms the bottom of the upper section of the cabinet, and this section is divided longitudinally into two chambers, one, 13, being a receiver of crushed or broken ice, and having a door, 14, by which access is given to this chamber. In front of the vertical partition, 15, is a second chamber and in this chamber the syrup jars or bottles, 16, are designed to be arranged in a row, each of these bottles being inverted

in use, and its neck-portions being adapted to fit tightly against a gasket or rubber ring, 17, surrounding the upper end of a funnel 18, into which the jar or bottle discharges its syrup, said funnel having a delivery pipe, 19, controlled by a needle, or other valve, 20, and leading the syrup into the mixing chamber of the usual dispensing faucet, 21, the construction of which may be of any well known type, as for instance, the similar faucet commonly used in dispensing apparatus. The delivery end of this faucet is located a sufficient distance over the projecting front of the horizontal partition or shelf, 10, to allow a drinking glass to be positioned upon the projecting portion and to directly receive the dispensed liquid, the front edge of the shelf being upturned or having a lip, 22, which will prevent any displaced liquid from spilling over the front of the cabinet.

The dispensing faucet, 21, is also appropriately connected to a tube, 23, which delivers the carbonated or other water or like liquid into the mixing-chamber of the faucet to be associated with syrup supplied from a bottle or container. In the present instance, I locate in the bottom of the ice-chamber, 13, the receivers, 24 and 25, for the water and carbonic-acid gas, or similar gas, and which receivers may be of the usual type and so connected that the carbonated water will be delivered through a tube, 26, into a pipe, 27, which extends horizontally along the face of the partition, 28, said pipe extending substantially throughout the length of the front of the cabinet or casing and each of the dispensing faucets employed in the construction of the apparatus having its carbonated-water tube connected to the pipe, 27, so that it may be supplied therefrom.

The pipes for the delivery of the carbonated water and the syrup pass through a marble or other vertical slab, 30, through which also passes the needle-valve of each of the syrup pipes, and the back of the faucet is designed to fit closely against the front face of the slab, said slab being therefore, set back a sufficient distance from the front edge of the shelf or partition, 10, and the corresponding edge of an apertured shelf or partition, 31, which supports the syrup bottles in their inverted position, so as to maintain the dispensing faucets substantially within the limits of the plane of

the front of the cabinet, and thus prevent their projecting beyond the front of the cabinet, to any appreciable extent.

In order that the syrup bottles may be open to observation at all times and their condition noted by the public, and, further, to give to the apparatus a more attractive appearance, the chamber in which the several jars or bottles with their vari-colored fluids are contained is provided with a glass front and which front comprises the sliding or other doors, 32, having appropriate handles by which the doors may be moved to give access to the interior of the space and to any of the bottles contained therein. This arrangement, while leaving the bottles in full view, permits the jar-containing space to be practically sealed against the entrance of dust or foreign matter and thus renders the apparatus more sanitary.

The partition, 15, which divides the bottle-containing chamber from the rear ice chamber, 13, is preferably of an open-work character, and therefore, I may make this portion of the partition of heavy screen-wire or the like. This will prevent the ice in the rear chamber from falling into the front chamber and against the jars or bottles, but at the same time it will enable the cold air of the rear chamber to be brought into direct contact with the bottles and thus insure the contents of said bottles being kept at a proper temperature.

An apparatus constructed and arranged as heretofore described offers the following advantages: It is of a most sanitary character; it enables the merchant to give better and quicker service and affords him opportunity of an attractive display of the syrups, which latter are maintained in a uniform condition, and there is a total absence of metallic parts with which the syrups can contact. It also enables any one or more of the jars or bottles to be removed without in any manner delaying or interrupting the service and it requires cleanliness on the part of the merchant for the reason that the syrups, their containers, and

in fact the active portions of the entire apparatus are visible to the customer. These are only some of the advantages which flow from the aforesaid construction; others will be apparent to those skilled in this particular art.

Having thus described my invention what I claim as new and desire to secure by Letters Patent is:

An improved dispensing apparatus comprising a cabinet or casing having a horizontal shelf or partition dividing the cabinet into upper and lower compartments, said upper compartment having a vertical partition dividing it into front and rear compartments, said rear compartment adapted as an ice chamber and having a door-controlled opening, and said front compartment having a bottom spaced from the forward portion of the first-named shelf or partition, and provided with openings; funnels fitted to said openings and each having a valve-controlled delivery tube; inverted syrup jars having necks fitting into the funnels; a pipe extending horizontally along the front of said vertical partition between said apertured bottom and said horizontal shelf and having distributing tubes; containers in the ice-chamber of the cabinet having means for supplying said horizontal tube with carbonated liquid; a vertical slab spaced from said vertical partition and extending between the horizontal shelf and said apertured bottom of said front chamber and spaced from said vertical partition, and through which slab the distributing tubes of said funnels and said horizontal pipe pass; a dispensing faucet for each jar or bottle fitted to said distributing syrup and liquid tubes and disposed in the space in front of said slab between the front portion of said apertured bottom and the corresponding portion of said shelf; said cabinet having a transparent front for the bottle-receiving chamber thereof.

In testimony whereof I affix my signature.

CHARLES JOHN DREWES.
